QUADRANTAL COMPENSATOR

William P. Lear, Dayton, Ohio, assignor, by mesne assignments, to Lear Avia, Inc., Piqua, Ohio, a corporation of Illinois

Application July 11, 1940, Serial No. 344,854

6 Claims. (Cl. 74—63)

This invention relates to quadrantal corrector mechanisms for effecting bearing compensations in radio direction indicator systems. The present case is a continuation-in-part of my copending application, Serial No. 311,313, filed December 28, 1939, which issued on September 22, 1942, as Patent No. 2,296,285, and assigned to the same assignee.

In accordance with the present invention, I provide improved constructions for quadrantal error compensation of indications of a radio direction finder. The system of the invention is particularly applicable to automatic direction finders operable over 360° of arc, such as disclosed in my copending application, Serial No. 286,733, filed on July 27, 1939, which issued on January 19, 1943 as Patent No. 2,308,521. Means are provided to quickly convert the corrector mechanism for different radio frequency bands of operation, enabling a busy pilot of an aircraft to readily effect a change. The mechanism comprises linked arms provided with a novel spring arrangement insuring uniform pressure between the corrector cam and cam follower throughout their 360° of operation despite movement between the minimum and maximum degrees of compensation, or wear. The cam blank is inscribed with a predetermined graphic representation permitting direct calibration and simple construction of the compensator cam for the mechanism.

It is accordingly an object of my present invention to provide a novel bearing compensator mechanism for a radio direction finder installation.

Another object of the invention is to provide a quadrantal error corrector with readily replaceable cam means for quickly converting the system to any one of a plurality of ranges of radio operation.

Still another object of the present invention is to provide a novel quadrantal error corrector arrangement with substantially uniform cam follower pressure throughout its 360° of operation and range of compensation.

A further object of the invention is to provide a novel compensator mechanism comprising linked arms with a spring biasing arrangement exerting uniform radial pressure over wide degrees of compensation.

Still a further object of the invention is to provide a corrector cam blank inscribed with predetermined graphic representations for effecting direct quadrantal error compensation calibration.

These and other objects of the present invention will become more apparent in the following description of a specific embodiment thereof illustrated in the accompanying drawings, in which:

5 Fig. 1 is a plan view, partially broken away, of the quadrantal error corrector embodiment with its cover open.

Fig. 2 is a vertical cross-sectional view through the corrector, with the cover closed, corresponding to a line 2—2 taken along Fig. 1.

Fig. 3 is an enlarged perspective illustration of details comprising the compensator mechanism.

Fig. 4 is a plan view of the inscribed quadrantal error corrector cam blank.

15 The compensator embodiment chosen to illustrate the present invention is arranged for coupling between a rotatable directional or loop antenna and the direction or bearing indicator. The compensator renders the bearing indications correct throughout the 360° of operation of the directional antenna. By employing the compensator or corrector in an automatic direction

20 finder system, direct bearing indications are obtained, eliminating interpolation or calculation.

25 The compensator of the present invention may well be used in the automatic radio direction indicator disclosed in my Patent No. 2,308,521, referred to above. The quadrantal error corrector schematically indicated in Figs. 7, 8 and 9 there-in may well be the compensator of the present invention. As is known by those skilled in the art, non-symmetry of metallic objects surrounding the rotatable directional antenna results in the quadrantal errors to be compensated for. The 30 calibration of the compensator depends upon the physical characteristics, particular installation, and the frequency range of the radio reception.

The quadrantal error corrector of the invention is designed as a unitary structure enclosed in a

40 housing 10 having a lid 11 hinged at 12, and attached by screws 14 to base 15. The compensation mechanism is coupled to shaft 16 of the directional or loop antenna (not shown), through an opening in base 15. The loop antenna may be

45 mounted beneath or above the corrector mechanism, in accordance with the installation requirements. When mounted above, the corrector is turned about from the position illustrated. Loop shaft 16 is coupled to rod 17 of the corrector

50 through flexible coupling unit 18. Coupling 18 comprises flexible disks 19 spaced by washers 20 and secured together by rivets 21. Small axial misalignments encountered between the corrector mechanism and the loop shaft 16 during installation or otherwise, accordingly do not affect the

calibration or operation of the system. A flexible cable 22 is coupled to the corrector mechanism for connection to the bearing indicator, not shown.

A feature of the present invention is the assembly of the compensator, motive drive therefor, and coupling gearing into a unitary arrangement. As shown in Fig. 1, a reversible electric motor 23 is contained within the compensator structure, coupled to horizontal rod 24 thereof through reduction gearing 25, 26 and magnetic clutch 27. Reversible motor 23 and magnetic clutch 27 are interconnected to the radio direction finder control system through electric cable 28. Preferred arrangements and connections for the motor, clutch and drive are disclosed in the Patent No. 2,308,521. With this arrangement, the motor and clutch are electrically shielded from the exterior by metallic housing 10 as well as the internal metallic supporting structure 28. Radio interference waves caused by the operation and interruptions of the motor and clutch are reduced in intensity or otherwise prevented from being picked-up by the radio antennae. Base 15 is preferably metallic to enhance the radio shielding of the enclosed electric motor drive.

Quadrantal error compensation is effected by imparting predetermined relative angular disbursements between loop shaft 16 and indicator shaft 22 as determined by a calibrated cam 30. The effective cam surface 31 of cam 30 coacts with its cam follower 32, radially spring biased by a trolley composed of linked arms 33, 34, 35, 36. The quadrantal error compensator of the invention, including the internal cam and trolley arrangement, corresponds to the corrector disclosed in my Patent No. 2,296,285 referred to above. Details of design, construction and advantages thereof, will be described in more detail hereinafter in connection with Fig. 3.

An important feature of the present invention resides in the ready replaceability of the corrector cam 30. Since modern radio direction finders are operable on several radio communication bands, and the effective calibration of the cam is different for widely separated bands, a cam change is preferable for accurate results. When the direction finder is used aboard an aircraft, a quick and positive change-over of the cam is important when indicated. In accordance with the invention, the outer periphery of the cam rests against spaced washers 37, 37 having overlapping raised ends. A spring clip 38 presses against straight edge 39 on the side of cam 30, opposite washers 37, 37. Clip 38 projects over the top surface of cam 30 to hold the cam down within coacting recesses in its supporting structure 41. A screw 40 or other suitable projection is arranged in cam 30, coacting with a hole in one of the cam supporting members 41, to predetermine the position of cam 30.

Cam 30 is accordingly readily removed from the structure by simply pressing clip 38 outwardly, raising the adjacent cam edge 39 upwardly, and then sliding it out from under overlying edges of washers 37, 37. A new cam may thus be quickly substituted by sliding it under the projecting edges of washer 37, 37, pressing cam follower 32 inwards radially, and moving the cam edge (corresponding to 39 of cam 30) under clip 38. The rounded projection of clip 38 permits the cam edge to be pressed down against it, whereupon spring 38 moves to hold the cam in its final level position. The cam is necessarily fitted in proper relation with respect to the mech-

anism, otherwise projecting screw 40 prevents its final insertion. Access to cam 30 is readily afforded by opening lid 11 through thumb screw 42 operating on element 43 arranged to be drawn 5 against the adjacent edge of housing 10.

Cam 30, cam supporting members 41, and linked trolley 33 to 36 of the quadrantal error corrector mechanism, are supported on a shelf 44 arranged above central supporting structure 28. Horizontal drive rod 24, directly coupled to motor 23 as previously described, is rotatably supported in structure 28. A horizontal shelf 45 is arranged beneath shaft 24, and held against the horizontal section of structure 28 by a nut 46 threaded on an extension of sleeve 47 concentric about corrector shaft 17. An assembly is provided for holding the mechanism above shelf 45, in operative and in 360° rotational condition. A nut member 48 rests between the unpivoted end of link 36 above shelf 44; and the hub of worm gear 50 below shelf 44, projecting through an opening therein.

A worm 49 is secured to horizontal shaft 24 and coacts with a worm gear 50 secured to a tubular shaft or sleeve 57 directly concentric about shaft 17 and connected with link 36. Shaft 17 and sleeve 57 thereabout are freely rotatable with respect to each other, and are respectively coupled to linked trolley 33-36 and worm gear drive 48, 50 in a manner to be more fully described in connection with Fig. 3. Indicator cable 22 is removably coupled to corrector shaft 24 by coupling piece 51. A coupling element 52 is arranged at the opposite end of shaft 24 in the event that a second indicator is to be coupled thereto, or that coupling is desired from that end of the unit. A bearing block 53 is attached to housing 10 about cable 22.

Fig. 3 is an enlarged perspective view diagrammatically illustrating the preferred arrangement for the quadrantal error corrector mechanism of the invention. Cam follower 32 is securely mounted on link 35 of the trolley to keep its contact point 52' at a predetermined relative displacement with respect to the trolley and cam. Cam follower 32 is preferably made of material having wear resistant qualities and low sliding friction coefficient on metallic cam surface 31, such as of fine fibre or graphite impregnated Bakelite. Arms 33, 34, 35, 36 are pivotally linked together. Screw members 51' are indicated for linking the arms and holding them stably together. However, other suitable means may be used. End 53' of link 33 contains an opening which closely fits onto the top end of central shaft 17. End 53' of link 33 is adjustably secured to shaft 17 by means of a slotted end 54 extending to its opening coacting with shaft 17 and a screw 55 threaded into the resultant end parts 56, 56. Screw 55 preferably projects somewhat from link 33 and has a knurled head, to permit convenient access thereto and manipulation thereof for angularly adjusting link 33 on shaft 17.

The unpivoted end of link 36 is similarly secured to the tubular shaft 57 concentric about shaft 17. The split end 58, 58 of link 36 is engaged by screw 59 to grip the top end of sleeve 57. Sleeve 57 and shaft 17 are freely relatively angularly displaceable with respect to each other. For a given setting of links 33 and 36 on shafts 17 and 57, the relative angular displacement between these shafts depends upon the radial position of cam contact 32 as controlled by cam surface 31 of cam 30. Calibrated variation of the 75 radial extension of cam follower 32, cam con-

trolled in accordance with its angular position, effects the quadrantal error compensation desired.

Central shaft 17 and link 33 of the trolley are in direct connection with the loop antenna, and rotate therewith without angular disparity. Sleeve 57 and link 36 of the trolley are in direct mechanical coupling with indicator shaft 22 extending to the azimuthal indicator of the system, with no relative angular displacement occurring between the indicator and link 36. The connection between link 36 and indicator cable 22 is as follows: Link 36 is secured to sleeve 57 as previously described. Sleeve 57 is directly connected with worm gear 50 through suitable set screws 60, 60 indicated in dotted lines in Fig. 3. Motivation of worm 49 by motor 23 through shaft 24 correspondingly turns worm gear 50 and sleeve 57, carrying therewith link 36 secured to the end of sleeve 57. Link 36 is rotatable in either direction, in accordance with the actuation of loop motor 23 under the control of the automatic direction finder. The indicator cable 22 is directly coupled to the compensator shaft 24, and therethrough to link 36 of the trolley.

Fig. 4 illustrates the cam blank used in constructing the corrector cam 30. The cam blank 30' is similar to that disclosed in my Patent No. 2,296,285 referred to above. The cam blank has inscribed thereon a 360° graph designed to translate the quadrantal error determinations on the direction finder installation by a direct, accurate and simple manner. A series of concentric circles 65 correspond to the magnitude of the quadrantal error, in degrees, as determined by experiment in the usual manner. The centrally disposed circle 66, labeled "0," corresponds to zero quadrantal error correction. The concentric circles radially larger than zero circle 66, refer to a negative (-) quadrantal error correction; the smaller circles, to a positive (+) quadrantal correction, as indicated in Fig. 4. Concentric circles 65 are shown spaced apart corresponding to two degree corrections. Other spacings are however feasible. Ready interpolation may be effected therebetween.

Arcuate radial lines 67 are arranged at 10° spacings over the 360° of arc. The arced calibration lines 67 are designed in accordance with the geometrical law of motion and coaction of cam contact 32 with respect to cam surface 31, which primarily depends upon the design, dimensions and arrangement of linked trolley 33-36. The curvature of lines 67 may be determined mathematically or empirically as preferred, to effect the respective positive and negative compensations. With the graphic calibration chart directly inscribed on cam blank 30', such as by printing, etching or the like, calibration of the cam may quickly follow from the quadrantal error determinations for the installation. The azimuthal scale on cam blank 30' of Fig. 4 reads ascending in the counter-clockwise direction since the particular cam is inserted face down in the corrector of Figs. 1 and 2. Due to set screw 40, the cam is insertable in the corrector in only one position, the proper one.

The quadrantal error compensation curve is plotted on the chart of cam blank 30'. In practice, the quadrantal error compensation determinations are preferably taken for each 10° of arc, and correspondingly plotted along spaced arcuate calibration lines 67 and circles 65. The smooth continuous curve connecting these points is thereupon determined on blank 30'. The cam

blank is then suitably cut out to derive internal calibrated cam 30. Cam edge 31 is smoothed to assure its smooth frictional engagement with contact point 52' of cam follower 32. When contact 52' is pressed inwards radially with respect to the mean or zero correction position of circle 66, links 33 and 36 are diverged, causing a corresponding increase in the angular relation between shafts 17 and 57. The resultant action 10 may be viewed as a correspondingly increased (clockwise) indicator reading for a given orientation of the loop antenna. Conversely, when contact 52' is permitted to move outwards radially, the angular relation of shafts 17 and 57 is decreased from the predetermined normal, effecting a virtual decreased (counter-clockwise) indicator reading. Complete and accurate quadrantal error compensation over the 360° azimuth may be thus effected with the system of the invention, which compensation is automatically and continuously present for all indications.

An important feature of the invention is the insurance of substantially uniform pressure of cam contact 52' on the cam and avoidance of 25 back-lash despite wide radial displacements of the trolley or of wear. Towards this end I provide spring 70 in the trolley to effect the continuous mechanical biasing radially outwardly of cam follower 32, arranged with respect to links 33-36 in a novel and advantageous manner. One end of spring 70 is anchored in link 34 at a predeterminedly located hole 71 therein. The other end of spring 70 is anchored in hole 72 of opposite link 36. The inside portion 73 of link 36, near its pivotal joint 51' with link 35, is undercut to permit the associated end of spring 70 to ride under link 35 at reduced angles between links 35 and 36.

Through extensive determinations, I have 40 found that the above described arrangement of spring 70 in the four arm trolley 33-36, affords a substantially uniform pressure for radially biased contact point 52' against cam surface 31. The uniform cam contact pressure is present 45 throughout the relatively wide radial displacement of the trolley system despite usual wear in the respective components of the compensator unit, and provides negligible backlash in the system. The substantially uniform cam follower 50 pressure and negligible backlash of the preferred arrangement occurs in the range between the minimum and maximum compensation positions of the system.

The principle of the preferred arrangement of 55 biasing spring 70 with respect to the four trolley links 33-36 is to anchor one end of the spring very close to an intermediate pivot 51', (such as between links 35 and 36), and to anchor the other end of the spring at an intermediate portion of an opposite link (such as link 34), at a position near the pivot diagonally opposite the first mentioned one. Thus, one anchor of spring 70 is at hole 72, with undercutting 73 affording an anchorage as close to pivot 51' between links 60 35, 36 as is practicable; the opposite anchor for spring 70 being at 71 on link 34. The choice of 65 anchor position 71 on link 34 is somewhat critical to give the substantially uniform cam contact pressure condition. The actual location of point 70 71 is preferably determined empirically. In experimental determinations, the location of anchor point 71 on a link corresponding to 34 was in the range of 20 to 40 percent of the length of link 34 from the pivot 51' between arms 33 and 34. Spring 70 is under tension.

Although I have disclosed preferred arrangements for carrying out the principles of my present invention, I am aware that modifications falling within the broader spirit and scope thereof are feasible, and accordingly I do not intend to be limited except as set forth in the following claims.

What I claim is:

1. In a quadrantal error corrector having an internally calibrated cam surface, a shaft, a sleeve concentric with said shaft, mechanism coupling said sleeve and shaft for predeterminedly controlling their relative angular displacement while permitting rotation thereof including a cam follower for coacting with the internal cam surface, a trolley forming a closed linked arrangement and carrying said cam follower, the unpivoted ends of said trolley being respectively secured to the ends of said shaft and sleeve, and a spring normally biasing said cam follower radially outwards against the cam surface, a gear secured to said sleeve, and an indicator shaft geared to said gear.

2. In a quadrantal error corrector having an internally calibrated cam surface, a shaft, a sleeve concentric with said shaft, mechanism coupling said sleeve and shaft for predeterminedly controlling their relative angular displacement over 360° of arc while permitting rotation thereof including a cam follower for coacting with the internal cam surface, a first link engaged with said shaft, a second link engaged with said sleeve, elements joining said first and second links and carrying said cam follower, and a spring for normally biasing said cam follower radially outward against said cam surface, said spring being anchored on said elements and said links in a manner to provide substantially uniform pressure of said cam follower against the internal cam surface through the compensation range, a gear secured to said sleeve, and an indicator shaft geared to said gear.

3. In a quadrantal error corrector: a frame; a corrector cam plate having a central pre-shaped cam surface opening; fastening means for removably engaging said cam plate in a predetermined relation on said frame including a plurality of spaced elements having a portion projecting over recesses in said frame for receiving corresponding portions of the outer periphery of said cam plate, an index projection on said cam, and a spring clip fastened on said frame for snapping against to the outer periphery of said cam plate when said index projection is in a predetermined opening of said frame to stably hold said cam in said recess.

4. In a quadrantal error corrector a shaft, a sleeve concentric with said shaft, mechanism coupling said sleeve and shaft for predeterminedly controlling their relative angular displacement over 360° of arc while permitting rotation thereof including a cam follower for coacting with an internal cam surface, a first link engaged with said sleeve, a second link engaged with said shaft, a third and fourth link respectively interlinking with said first and second links and carrying said cam follower, and a spring anchored between the end of said first link which joins said third link and an intermediate portion of said fourth link in a manner to provide substantially uniform pressure of said cam follower against said internal cam throughout a relatively wide compensation range, said first link end being undercut at the spring anchor position to permit said third link to freely pivot thereover.
5. In a quadrantal error corrector a first and second shaft, mechanism coupling said shafts for predeterminedly controlling their relative angular displacement over 360° of arc while permitting rotation thereof including a cam follower for coacting with an internal radially calibrated cam surface, a first link engaged with said first shaft, a second link engaged with said second shaft, a third and fourth link respectively interlinking with said first and second links and carrying said cam follower, and a tension spring anchored between the end of said first link which joins said third link and an intermediate portion of said fourth link located at a distance in the range of 20 to 40 percent of the fourth link length from its connection to said second link in a manner to provide substantially uniform pressure of said cam follower on said internal cam throughout a relatively wide compensation range.
6. In a quadrantal error corrector having an internally calibrated cam surface, a shaft, a sleeve concentric with said shaft, mechanism coupling said sleeve and shaft for predeterminedly controlling their relative angular displacement while permitting rotation thereof including a cam follower for coacting with the internal cam surface, a trolley forming a closed linked arrangement and carrying said cam follower, the unpivoted ends of said trolley being respectively adjustably secured to the ends of said shaft and sleeve, and a spring normally biasing said cam follower radially outwards against the cam surface, a gear secured to said sleeve, and an indicator shaft geared to said gear.

WILLIAM P. LEAR.
